UNITED STATES PATENT OFFICE.

BURR CUSTER, OF MARION, INDIANA.

TORCH.

1,137,191.

Specification of Letters Patent. Patented Apr. 27, 1915.

Application filed July 3, 1914. Serial No. 848,843.

To all whom it may concern:

Be it known that I, BURR CUSTER, a citizen of the United States, and a resident of Marion, in the county of Grant and State of Indiana, have invented certain new and useful Improvements in Torches; and I do hereby declare the following to be a full, clear, and exact description of the invention, such as will enable others skilled in the art 10 to which it appertains to make and use the same.

This invention relates to improvements in torches,—one object of the invention being to so construct the device that it may be used either as a welding or an illuminating torch, and to provide means whereby the operator may easily and quickly manipulate the same with the use of one hand to transform the device from one character of torch 20 to the other.

A further object is to provide simple and efficient means for controlling the quantity and mixture of gases employed to effect an illuminating flame or a welding flame of the 25 desired volume or intensity.

With these and other objects in view, the invention consists in certain novel features of construction and combination of parts as hereinafter set forth and pointed out in the 30 claims.

In the accompanying drawings, Figure 1 is a view partly in section and partly in elevation illustrating my improvements. Fig. 2 is an enlarged sectional view showing the 35 valve mechanism. Fig. 3 is a separate view in elevation of the valve, and Fig. 4 is an enlarged detail sectional view showing the connection between the oxygen and acetylene pipes.

40 Fig. 1 represents a valve casing, to which two cylinders or receptacles 2, 3 are suitably secured (preferably in front and in rear respectively of said casing), and communicate with the latter by means of ducts 4—5 and ports 6—7. A pipe 6^a communicates with the cylinder or receptacle 2 for conducting acetylene gas thereto from a suitable source 45 of supply. The chamber of this cylinder or receptacle may contain a quantity of metallic shavings, such as steel "moss," and in order to prevent the shavings from entering the duct 4 and pipe 6^a, diaphragms 7^a of wire netting may be employed.

A pipe 8 is connected with the casing 1 55 and communicates with a port 9 therein to receive acetylene gas in the manner herein-

after described,—the forward portion of said pipe 8 being curved and provided at its free end with a burner head 10.

A pipe 11 (adapted for connection with a 60 suitable source of oxygen supply) is connected with the casing 1 so as to communicate with a port 12 located therein opposite the port 7.

The cylinder 3 has connected with its forward end, a pipe 13 (preferably smaller in size than the pipe 8) and the forward portion of said pipe 13 is bent to lie alongside the pipe 8,—the forward end of the pipe 13 being connected with the pipe 8 by means of 70 a tubular nipple 14 which enters both of said pipes and is made with perforations communicating with the respective pipes. The cylinder 3 may contain metal clippings (preferably brass or bronze), and said clippings are prevented from entering the port 7 and pipe 13 by means of diaphragms 75 15 of wire netting.

The supply of acetylene gas or oxygen or both to the burner head, may be readily controlled and regulated by means of valve devices disposed between the ports 6—9 and 80 7—12. These devices comprise a conical plug valve 16 mounted in a suitable bore in the casing 1 and provided at its lower end 85 with a stem 17 depending below said casing.

Two collars 18—19 are located on the stem 17, near respective ends thereof and between these collars, a spring 20 is located on the stem and serves to retain the plug valve 90 properly in place and to compensate for wear. The plug 16 is provided in its lower portion with a transverse duct 21 located at one side of the longitudinal center of the plug and adapted to connect the ports 12 95 and 7. For the purpose of permitting the plug to be readily turned by the operator to control the supply of oxygen, said plug is provided with a finger lever 22 projecting laterally therefrom, and to limit the rotary 100 movements of the plug, the latter is provided with a pin 23 movable from end to end of a slot 24 in the upper portion of the casing 1.

The plug 16 is made with a duct 25 to 105 communicate with the port 6 in the casing, and said plug is also made with a duct 26 to communicate with the port 9,—said ducts 25 and 26 being also adapted to communicate with each other. A valve 27 extends downwardly into the upper portion of the plug 16 so as to intersect the ducts 25—26 and

control the passage of acetylene gas through these ducts. The valve 27 is made with a threaded portion 28 to mesh with a similarly threaded portion within the plug and the upper end of the stem of this valve is provided with a hand wheel 29 to facilitate the manual operation of the same. The upper end of the stem of the valve 27 passing through a packing box 30 screwed onto a threaded shank 31 at the upper end of the plug 16.

It will be observed that the ends of the ducts in the plug 16 are each of less diameter than the diameter of the respective ports 6, 7, 9 and 12 and that the duct 21 in the plug is at one side of the axis of the plug. By this arrangement, the plug may be turned to such position as to connect the acetylene gas ducts 25-26 with their ports, while communication between the oxygen ports 7-12 is kept closed, or so that the ducts 25-26 and 21 may be caused to communicate with their respective ports and thus permit the supply of both gas and oxygen to the burner head.

When it is desired to use the torch for welding purposes, the plug will be turned by means of the finger piece 22 in such manner as to permit the supply of both acetylene gas and oxygen to the burner head. The amount of the mixture may be regulated by the extent to which the plug is turned, while the relative proportions of gas and oxygen may be regulated by means of the valve 27.

When it is desired to use the device temporarily as a lighting torch to permit the operator to inspect his work,—this may be quickly accomplished by turning the plug

sufficiently to close the duct 21 and opening the valve 27 more or less to control the supply of only acetylene gas. The device may be as quickly again converted into a welding device by reversing such manual operation of the valve mechanism.

Having fully described my invention what 45 I claim as new and desire to secure by Letters-Patent is:

1. In a torch, the combination with two cylinders, and a casing disposed between said cylinders and communicating with both, of a gas inlet pipe communicating with one of said cylinders, an oxygen inlet pipe communicating with said casing, a gas outlet pipe communicating with said casing, a burner head on said gas outlet pipe, an oxygen outlet pipe communicating with the other cylinder and said gas outlet pipe, and a valve device in said casing and common to both cylinders and their pipe connections. 55

2. In a torch, the combination with gas and oxygen pipes communicating with each other, and a burner head on the gas pipe, of cylinders in the circuits of said pipes, a plug valve common to both of said pipes, manually operable means for operating the 60 plug valve, and another manually operable valve mounted in the plug for separately controlling passage of gas through the gas pipe to the burner head. 65

In testimony whereof, I have signed this 70 specification in the presence of two subscribing witnesses.

BURR CUSTER.
